(57) **CLAIM**

The ornamental design for a connector housing, as shown and described.

DESCRIPTION

FIG. 1 is a front top perspective view of a connector housing showing our new design;

FIG. 2 is a front bottom perspective view thereof;

FIG. 3 is a rear perspective view thereof;

FIG. 4 is a front view thereof;

FIG. 5 is a rear view thereof;

FIG. 6 is a bottom view thereof;

FIG. 7 is a top view thereof;

FIG. 8 is a right side view thereof;

FIG. 9 is a left side view thereof;

FIG. 10 is a front top perspective view of an alternate embodiment of a connector housing showing our new design;

FIG. 11 is a front bottom perspective view thereof;

FIG. 12 is a rear perspective view thereof;

FIG. 13 is a front view thereof;

FIG. 14 is a rear view thereof;

FIG. 15 is a bottom view thereof;

FIG. 16 is a top view thereof;

FIG. 17 is a right side view thereof;

FIG. 18 is a left side view thereof;

FIG. 19 is a front top perspective view of an alternate embodiment of a connector housing showing our new design;

FIG. 20 is a front bottom perspective view thereof;

FIG. 21 is a rear perspective view thereof;

FIG. 22 is a front view thereof;

FIG. 23 is a rear view thereof;

FIG. 24 is a bottom view thereof;

FIG. 25 is a top view thereof;

FIG. 26 is a right side view thereof;

FIG. 27 is a left side view thereof;

FIG. 28 is a front top perspective view of an alternate embodiment of a connector housing showing our new design;

FIG. 29 is a front bottom perspective view thereof;

(Continued)

FIG. 30 is a rear perspective view thereof;
 FIG. 31 is a front view thereof;
 FIG. 32 is a rear view thereof;
 FIG. 33 is a bottom view thereof;
 FIG. 34 is a top view thereof;
 FIG. 35 is a right side view thereof; and,
 FIG. 36 is a left side view thereof.

The broken lines immediately adjacent to the shaded areas represent the bounds of the claimed design and form no part thereof. The broken line showing within the shaded areas represent features that form no part of the claimed design. The broken lines depicting the remainder of the connector housing show features that form no part of the claimed design.
